UNITED STATES PATENT OFFICE

RAYMOND CALPIN, OF EVERETT, MASSACHUSETTS, ASSIGNOR TO A. S. CAMPBELL COMPANY, OF EAST BOSTON, MASSACHUSETTS, A CORPORATION OF MASSACHUSETTS

AUTOMOBILE BODY AND METHOD OF CONSTRUCTING A BODY

Application filed September 17, 1928. Serial No. 306,463.

This invention relates to vehicles of the closed type, and more particularly though not exclusively to those permanently closed as distinguished from convertible vehicles, and the object is to provide an improved construction for the forward part of the body enclosure in itself offering many advantages in production and in use, as will appear to those skilled in the art from the following 10 description of illustrative embodiments thereof, and which also, in its preferred form, makes possible a novel and advantageous method of building or assembling the body.

The invention applies particularly to 15 those bodies in which the forward body pillars arising adjacent the cowl, or at least such portions thereof as extend above the belt line to support the roof, are made of metal, a construction utilized particularly 20 to restrict the dimension of the corner assemblies lying in the field of the driver's vision, preferably to a dimension not less than the distance between the eyes as described in the Emond Patent, No. 1,622,098, March 22, 25 1927.

The invention will be understood by reference to the following description taken in connection with the accompanying drawings wherein:

30 Fig. 1 is a fragmentary, broken away perspective of a partly completed automobile body, the left hand or nigh corner being shown, and with a part displaced;

35 Fig. 2 is a section through the front of the vehicle looking toward the inner side of the body pillar shown in Fig. 1;

Fig. 3 is a front elevation of the main portion or body of said pillar detached;

40 Fig. 4 is a front elevation of a finishing section which completes the contour of the pillar;

Fig. 5 is a section on the line 5—5 of Fig. 2;

45 Fig. 6 is a section on the line 6—6 of Fig. 5;

Fig. 7 is a front elevation of the body portion of a body pillar for a vehicle having a swinging windshield, the nigh pillar being shown;

50 Fig. 8 is a similar view of a cooperating detachable section for use therewith;

Fig. 9 is a side elevation of said section as seen from the nigh side;

Fig. 10 is a similar side elevation of the body portion of the pillar; and

Fig. 11 is a cross-section on a larger scale 55 through said parts in assembled position, in the plane of line 11—11 of Figs. 7 and 8.

In order expeditiously to disclose my invention, I shall first describe the structural elements utilized in the illustrative embodiment of Figs. 1 to 6 and thereafter will indicate the novel method of body building which may be practiced in connection with their use. Referring therefore to Figs. 1 to 6

of the drawings, I have there shown a construction adapted for use in an automobile of composite construction having a windshield confined in an upright plane, for example, a vertically sliding as distinguished from a swinging windshield. The standing body 70 pillar or at least that portion thereof which pertains to the upper portion or top of the body above the belt line is constructed of metal, and is herein shown as comprising a main member or body of suitable tough metal, 75 preferably a drop forging, comprising a substantial, transverse web 11, the lower portion of which extends downwardly at 13 and is incorporated with the framework of the vehicle below the belt, herein by being secured to the rear face of the upright frame member 15 at the cowl. Extending inwardly from this web there may be provided an arm 17 to be secured to the cowl bar 19. Preferably the

80 forging is provided at the belt with the box-like reinforcement 21 which may also be utilized to provide a mortise for the leaves of the door hinge. At the upper end suitable arms 23 and 25 are provided for securing it to the framing members of the roof, herein respectively the longitudinal side rail 27 and the transverse front rail 29 forming the front 85 wall of a header into which the windshield glass 31 lifts when raised by means of suitable hoisting mechanism, not shown. To stiffen the web and for other purposes which will appear, it may be provided on its forward face (see Figs. 3 and 5) with an integral rib 90

31 which may merge into the box-like reinforcement 21.

95

Fig. 11 is a cross-section on a larger scale 100 through said parts in assembled position, in the plane of line 11—11 of Figs. 7 and 8.

forcement 21 and which gives the upper portion of the pillar a T section.

The exterior contour of the pillar as a whole and preferably finished surfaces thereof which are exteriorly exposed in the finished vehicle are provided for by a separable member 35 adapted to fit over and be detachably secured to the body member just described, and this separable member preferably takes the form of an aluminum die-casting. In the embodiment of the invention shown (see Fig. 5) the die-casting 35 is adapted to overlie the forward end of the rib 33 and to fit into and fill the rabbet defined on the outer side between this rib and the body of the web 11, and it may extend somewhat beyond the outer edge of the web to provide a rabbet 37 to receive the overlap flange of a door closing against the pillar. The die-casting 35 is also provided with a flange 39 extending inwardly and adapted to oppose the inner portion of the web 11 and define therewith a channel receiving the edge of the windshield glass and the felt-lined channel 41 in which it moves.

As will be apparent from Fig. 5, all the surfaces of the post which are exteriorly exposed in the finished job are provided by the die-casting 35. This is made of any suitable contour as dictated by the design of the vehicle. Thus, as indicated in Figs. 3 and 4, it is provided with a suitable foot portion 43 following the lines of the cowl and a suitable head 45 harmonizing with the top of the vehicle and is given such curvilinear outline or paneled surface as may be desirable. In the drawing (Fig. 4) the enlarged portions at the top and bottom of the post have been shown cored out. The foot 43 may overlie the cowl panel 47 as shown in Fig. 2.

The die-cast section 35 is suitably secured to the forged body of the post, preferably (see Fig. 5) by means of screws 49 entering through the web 11 of the die-cast member from the back and tapping into the cast member 35 without intersecting the exposed surfaces thereof, thus providing a particularly neat finish. To aid in relatively positioning the parts, one of the members, such as the die-cast section 35 (see Fig. 6) may be provided with small protuberances 51 adapted to enter suitable recesses 53 in the other section, herein in the forward face of the rib 33 (see Fig. 1.)

A construction such as that exemplified by Figs. 1 to 6 provides for a method of assembly of the body having marked advantages. Thus referring to Fig. 1, the body may be completely framed with the forged body 11 of the pillar secured in position and the roof hung and permanently secured thereto as indicated graphically in Fig. 1 by the showing of the roof rails 27 and 29. The cowl panel 47 may then be applied, shaped into form about the cowl frame and nailed in position thereon,

its edge being presented to the front face of the forging, as seen in Fig. 1. Then, without any disassembling operations, the separable section 35 may be set against the front face of the forging 11 by a simple movement of approach in a substantially horizontal plane, as will readily be understood from Fig. 1, setting in between the cowl and the roof, and is easily secured in position by the screws 49. The foot portion 43 will overlie the edge of the cowl panel 47 at the front face of the forging and cover up the rough joint and the nails 55 which fasten the panel down.

The joint and its surface provided by the method of securing the cowl panel is comparatively rough. The section 35 is light and wieldy and the lower end thereof at foot 43, which may conveniently be made slightly oversized, may be most readily fitted to adapt it to the conditions of the particular body. It may readily be set against the body 11 to permit such fitting by a cut and try method. In such fitting the foot 43 may be so shaped as to provide, as seen in Fig. 2, an open joint 57 between the margin of foot 43 and the cowl panel, which is desirable in that it prevents a crack in the paint from appearing at this point, which in the absence of such an open joint appears inevitable.

In contrast with such a method as described in the case of a pillar embodying as an integral or effectively integral whole what herein forms the separable parts 11 and 35, the pillar would have to be removed from the framed-up body, leaving the roof pendulous, to permit application of the cowl panel and thereafter replaced. Moreover, such a one piece construction would be heavy and unwieldy not lending itself to easy alteration to provide for a proper fit and any cutting or grinding to provide such a fit would have to be done on the face of a rabbet instead of across a terminal surface as in the case of the member 35. (See Fig. 4.)

In Figs. 7 to 11, I have shown a construction adapted for use in a vehicle having a swinging windshield. In Figs. 7 and 10 there is shown the main section of the body pillar, preferably a drop forging, having a web 111 continued as an anchor 113, and also having the box-like reinforcement 121 at the belt and an arm 117 for anchorage to the cowl bar. At the upper end arms 123 and 125 are provided to be secured to the longitudinal and transverse frame members of the roof respectively. In the embodiment of the invention shown the upper portion of the pillar is provided with a rearwardly extending stiffening flange 126 at the inner side thereof providing a door stop. The forward outer portion of the web may be rabbeted as indicated at 128 (Fig. 11) to seat the body portion of the cooperating die-cast section 135 which projects forwardly to define with the forward face of the web 111 the rabbet 136 to

receive the windshield frame and may project outwardly beyond the outer edge of the web to provide a rabbet 137 to receive the overlap flange of the door. As before, the die-cast section is given such exterior contour as the design of the vehicle may call for and may be provided with the foot portion 143 to overlie the cowl panel and the top portion 145 merging with the lines of the top. The 5 section is secured in position by means of screws 149 passing through the web 111 and tapped into the section 135 from the rear, and it may be positioned vertically by means of suitable surfaces formed thereon cooperating 10 with surfaces on the forged section. Herein the box-like reinforcement 121 of the latter provides at the forward side suitable surfaces on which the lower portion of the die-cast section may fit, as indicated in Figs. 7 to 20 10. The upper body portion of the post 111 may be offset forwardly as illustrated in Fig. 10 to provide a recess 150 which may receive the leaves of the top hinge of the door in alignment with the leaves of the middle hinge 25 which are received in the box at 121 (preferably in such manner that both leaves of the hinge are disposed forwardly of the crack of the door) and the forward side of the offset 150 provides positioning surfaces cooperat- 30 ing with suitable hollow surfaces on the rear face of the upper end portion 145 of the die-cast section.

Obviously the description already given of the preferred method of incorporating the 35 structure of Figs. 1 to 6 in the body and the citation of some advantages of such a method apply to the construction of Figs. 7 to 11.

In describing the modification of Figs. 7 to 11, I have designated the parts corresponding 40 generally to parts in the modification of Figs. 1 to 6 by the number applied as a numeral to said latter parts increased by 100. Thus, in the modification of Figs. 1 to 6 the die-cast section is 35 and in the modification of Figs. 45 7 to 11 it is 135.

As the removable section may be separated bodily and by a simple lifting off movement, it is convenient to house the piping for the windshield wiper 59 in Fig. 5 and 159 in Fig. 50 11, in a suitable groove, 61 and 161 respectively, between opposed faces of the two sections, and, as well illustrated in Fig. 8, suitable passages, as 163 and 165, may be formed as a continuation of this groove to permit the 55 piping to be concealed through substantially its entire length. This arrangement is particularly desirable since if for any reason access to the piping must be had, the major portion of the piping is directly exposed when 60 the die-cast section is removed, and to remove it or replace it, it need be threaded only through short passages, such as 163 and 165.

In the embodiment of the invention shown 65 in Figs. 1 to 6 the sections 35 may be placed in position and the car painted and then readily

removed and the windshield inserted from the front and secured by said sections in alignment with its berth in the header adjacent the roof. It will be noted that in this modification a sliding windshield is provided for while a substantial and unbroken body of tough metal securely incorporated with the framework of the vehicle is found in the web 11. 70

In both the modifications described, 75 whether for a sliding windshield or a swinging windshield, the exposed surfaces of the post as a whole are provided for by the die-cast section 35 or 135. Thus, the body portion of the post embodying the web 11 or 111 may be made of a forging or similar metal which is tough and strong but which under the circumstances will not require any expensive machining or similar finishing but may be incorporated in relatively rough shape into the job. The removable section 80 may be die-cast immediately and cheaply to final form and need not be relied upon for strength, and as it comes from the mold is ready to be painted without any costly finishing operations. The body portion or drop forging of the pillar may be made standard for a wide variety of cars and thus but one set of expensive dies will be required. The style effect may be changed by associating 85 with this drop-forged body an easily made die-cast finishing piece which gives the desired exterior contour to the pillar as a whole and which preferably in itself provides the entire exposed surface of the finished job. 90

I have described in detail the illustrative embodiments of my invention shown by way of example in the accompanying drawings. Obviously the construction may be widely varied without departing from the principles 100 of the invention and what I claim as new and desire to secure by Letters Patent I shall express in detail in the following claims. 105

Claims:

1. The method of constructing automobile bodies which comprises constructing the body frame including top supporting body pillars arising adjacent the cowl and having the roof hung and permanently secured thereto, securing in position a cowl panel with edges presented adjacent the front of said pillars and then assembling with the pillars by a movement of approach in substantially a horizontal plane contour-completing sections having base portions to overlie said panel adjacent the pillars and mechanically securing such sections to the pillars. 110

2. The method of constructing automobile bodies which comprises constructing the body frame including top supporting body pillars arising adjacent the cowl and having the roof hung and permanently secured thereto, securing in position a cowl panel with edges presented adjacent the front of said pillars, seating against exteriorly presented surfaces 115 120 125 130

of said pillars contour-completing sections having base portions to overlie said panel adjacent the pillars and securing said section against said surfaces.

5. In a vehicle of the closed type a forward body pillar comprising a body of tough metal incorporated with the framework of the vehicle below the belt and with the roof, said body having a seat at its exterior face, and a member of varied cross section defining the exterior contour of the complete pillar and having an inherent self-maintaining shape fitting on said seat by a movement of lateral approach and mechanical fastening devices detachably securing it against the seat.

10. 4. In a vehicle of the closed type a forward body pillar comprising a body of tough metal incorporated with the framework of the vehicle below the belt and with the framework of the roof, said body having a seat at its exterior face, a contour-giving section having an inherent, self-maintaining shape received against said seat, the surfaces of said section providing the exteriorly exposed surfaces of the post as a whole and mechanical fastening devices securing said section thereagainst.

15. 5. In a vehicle of the closed type a forward body pillar comprising a body of tough metal incorporated with the framework of the vehicle below the belt and with the framework of the roof, said body having a seat at its exterior face, a contour-giving section having an inherent, self-maintaining shape received against said seat by a movement of lateral approach, the surfaces of said section providing the exteriorly exposed surfaces of the pillar as a whole, the cross-section of said contour-giving section being such as to provide in the assembly by cooperation with said body a door overlap rabbet and a windshield jamb frame and mechanical fastening devices securing said section thereagainst.

20. 6. In a vehicle of the closed type a forward body pillar comprising a body of tough metal incorporated with the framework of the vehicle below the belt and with the framework of the roof, said body having a seat at its exterior face, a contour-giving section having an inherent, self-maintaining shape received against said seat by a movement of lateral approach, the surfaces of said section providing the exteriorly exposed surfaces of the pillar as a whole, and means for securing said section to its seat comprising fastening devices entered through said body from the rear and engaging said section without intersecting the exposed surfaces thereof.

25. 7. In a vehicle of the closed type a top-supporting pillar comprising a body of tough metal incorporated with the framework of the vehicle below the belt and with the framework of the roof, and a section of inherent self-maintaining shape removably fitted thereagainst at the outer forward corner thereof, said parts when assembled defining

between them a bore for piping up a windshield wiper, said section completing the exterior contour of the pillar.

8. In a vehicle of the closed type a top-supporting pillar comprising a body of tough metal incorporated with the framework of the vehicle below the belt and with the framework of the roof and a die-cast section secured thereto and completing the contour of the pillar, the exposed surfaces of the pillar being surfaces of said die-cast section.

70. 9. In a vehicle of the closed type a top-supporting pillar comprising a metal body incorporated with the framework of the vehicle below the belt and with the framework of the roof, said body having a web and a forwardly projecting reinforcing rib defining rabbits at its sides, that at the inner side receiving the edge of a windshield, and a section completing the contour of said pillar fitting the outer rabbet and overlying the forward edge of said rib, the surfaces of said section providing the exteriorly exposed surfaces of the pillar as a whole.

75. 10. In a vehicle of the closed type a top-supporting pillar comprising a metal body having a web and a forwardly projecting reinforcing rib defining rabbits at its sides, that at the inner side receiving the edge of a windshield, and a section removably secured to said body to complete the contour of the pillar, said section fitting the outer rabbet and having a flange overlying the forward edge of said rib and extending beyond the same to confine the windshield in the inner rabbet, the surfaces of said section providing the exteriorly exposed surfaces of the pillar as a whole.

80. 11. In a vehicle of the closed type a top-supporting pillar comprising a body of tough metal presenting a forwardly facing recess having end and side surfaces and a section completing the contour of the pillar comprising a rigid member having a part to enter said recess and seat against the surfaces thereof, the surfaces of said section providing the exteriorly exposed surfaces of the pillar as a whole and mechanical fastening devices for securing the section to the said body.

85. 12. In a vehicle of the closed type having a windshield confined in an upright plane, corner pillars having forwardly facing rabbits receiving the edges of said windshield and removable sections having flanges overlying the edges of the windshield and confining them in said flanges, said sections defining the exterior contour of the pillars, said windshield being removable through removal of said sections.

90. 13. In a vehicle of the closed type a top-supporting pillar comprising a body of tough metal having a rabbet along its outer forward edge and a section seated in said rabbet completing the exterior contour of the pillar, the surfaces of said section providing the ex-

teriorly exposed surfaces of the pillar as a whole, and means for securing said parts together.

14. In a vehicle of the closed type a top-supporting pillar comprising a metal body, a section removably fitted at the outer forward corner thereof and having an inwardly projecting flange to overlie a windshield and confine it against said body, said section completing the exterior contour of the pillar and providing the exteriorly exposed surfaces of the pillar as a whole.

15. In a vehicle of the closed type a top-supporting pillar comprising a body of tough metal incorporated with the framework of the vehicle below the belt and with the framework of the roof, said body presenting a forwardly facing seat and a section completing the contour of the pillar comprising a rigid member having a part cooperating with said seat to be positioned thereby, on assembly therewith by a movement of lateral approach, the surfaces of said section providing the exteriorly exposed surfaces of the pillar as a whole, and means for securing said section to its seat.

16. In a vehicle of the closed type comprising a cowl, a pillar arising adjacent thereto comprising a body of metal incorporated with the framework of the vehicle and extending from below the cowl to the roof and a section overlying the cowl and of varied cross section to give the contour to the completed pillar between the cowl and roof, said section adapted to be seated against said body by a movement of approach substantially in a horizontal direction and fastening devices for removably securing said section seated against said body.

In testimony whereof, I have signed my name to this specification.

RAYMOND CALPIN.
